UNITED STATES PATENT OFFICE

92,392

DESIGN FOR ATHLETIC TROUSERS

Frank P. Dwyer, Philadelphia, Pa., assignor to Samuel Coane, Philadelphia, Pa.

Application June 24, 1933, Serial No. 48,519

Term of patent 7 years

To all whom it may concern:

Be it known that I, FRANK P. DWYER, a citizen of the United States and a resident of Philadelphia, in the county of Philadelphia and State of Pennsylvania, have invented a new, original, and ornamental Design for Athletic Trousers, of which the following is a specification, reference being had to the accompanying drawing forming part hereof, in which:

The dominant feature of my design consists of a balanced generally angular arrangement of contrasting colors to form the body and leg portion of the trousers.

I claim:

The ornamental design for athletic trousers as shown and described.

In testimony whereof, I affix my signature.

FRANK P. DWYER.
